UNITED STATES PATENT OFFICE

114,574

DESIGN FOR A SOLDERING IRON STAND

Leonard P. Young, Chester, Conn.

Application December 12, 1938, Serial No. 81,720

Term of patent 14 years

To all whom it may concern:

Be it known that Leonard P. Young, a citizen of the United States and resident of Chester, in the county of Middlesex and State of Connecticut, has invented a new, original, and ornamental Design for a Soldering Iron Stand, of which the following is a specification, reference being had to the accompanying drawing, forming part thereof, and in which the figure is a perspective view of a soldering iron stand showing my design.

The other side and rear end of the base are

substantially like the side and end shown and the rear and other side of the hood are substantially plain.

The characteristic features of my design reside in the base portion of the stand in combination with the hood and support superposed thereon, as shown.

I claim:

The ornamental design for a soldering iron stand, as shown and described.

LEONARD P. YOUNG.
